UNITED STATES PATENT OFFICE

EDWARD J. BURKE, OF CINCINNATI, OHIO, ASSIGNOR TO THE RICHARDSON COMPANY,
OF LOCKLAND, OHIO, A CORPORATION OF OHIO

DESIGN FOR A SHIPPING CRATE OR SIMILAR CONTAINER

Application filed January 19, 1931. Serial No. 38,359. Term of patent 14 years.

To all whom it may concern:

Be it known that I, EDWARD J. BURKE, a citizen of the United States, residing at Cincinnati, in the county of Hamilton and State of Ohio, have invented a new, original, and ornamental Design for a Shipping Crate or Similar Container, of which the following is a specification, reference being had to the accompanying drawing, forming part thereof.

In the drawing:

The figure is a perspective view of the shipping crate or similar container embodying my design. The cross-hatching in the drawing represents areas of contrasting color.

I claim:

The ornamental design for a shipping crate or similar container as shown in the drawing.

EDWARD J. BURKE.
